UNITED STATES PATENT OFFICE.

JOSEPH VIGLIANO, OF NEW YORK, N. Y.

VARIABLE-SPEED CONTROL MEANS.

Application filed January 16, 1926. Serial No. 81,632.

To all whom it may concern:

Be it known that I, JOSEPH VIGLIANO, a citizen of the United States, and a resident of the borough of Manhattan, city, county, and State of New York, have invented certain new and useful Improvements in Variable-Speed Control Means, of which the following is a specification sufficient to enable those skilled in the art to which the invention appertains to utilize the same.

My invention is the result of experimental investigation undertaken for the purpose of attaining simple, light weight, but effective variable speed mechanism adapted to uniform graduation from minimum to maximum degree, or vice versa, in contradistinction to restricted and prescribed step graduation as heretofore known in the art, so that power may be transmitted from a generating unit to operative receiving mechanism at any rate of velocity desired without the motion capacity provided for, an incidental feature being the elimination of the shifting of gears in changing from one speed to another; and the invention consisting essentially in the specific construction, combination and arrangement of component parts and appurtenances herein described and claimed, whereby these and other advantageous results are attained, all as hereinafter set forth.

In the accompanying drawings I illustrate a practical embodiment of the essential features of my invention in variable speed mechanism of the character designated, although I do not restrict myself to the identical form and construction of component parts of the apparatus shown by way of exemplification since changes may be made in minor details and equivalent mechanical expedients resorted to, with like results, and without departing from the spirit and intent of my invention in this respect.

45 With this understanding:—

Fig. 1, represents a plan view, with the casing broken away in part, and taken on plane of line 1—1, Fig. 2, of a preferred construction and arrangement of my improved variable speed transmitting mechanism, set for maximum speed;

50 Fig. 2, is a longitudinal vertical sectional elevation thereof, taken upon plane of line 2—2, Fig. 1;

Fig. 3, is a transverse vertical sectional elevation taken upon plane of line 3—3, Fig. 1;

Fig. 4, is a transverse vertical sectional elevation taken upon plane of line 4—4, Fig. 1;

Fig. 5, is a vertical sectional detail taken upon plane of line 5—5, Fig. 4;

Fig. 6, is a horizontal sectional detail taken upon plane of line 6—6, Fig. 5;

Fig. 7, is a view like unto Fig. 1, showing the variant slide set for medial speed;

Fig. 8, is a sectional elevation of a detail illustrating a modification in the means for adjusting the variant slide;

Fig. 9, is a sectional elevation in detail illustrating still another modification in the means for adjusting the variant slide;

Fig. 10, is a diagram illustrating the old method of step variation of speed;

Fig. 11, is a diagram illustrating my method of unrestricted speed variation.

In the first seven figures of the drawings the means provided for effecting the adjustment of the variant slide V, is a worm screw S, rotatively mounted at one extremity in a fixed bearing a, on the supporting framework A, of the apparatus, and engaging with a nut v, integral with said variant slide V, the outer extremity of said actuating screw S, being provided with a handle s, for manipulative purposes. In the modification shown in Fig. 9, the slide V, is coupled to the inner end of an actuating screw S', which is adjustable longitudinally in the fixed nut bearing a'; whereas in the modification illustrated in Fig. 8, a like result is attained by the substitution of a slide rod S², in lieu of a screw to the inner end of which slide rod S², the slide V, is coupled as in Fig. 9, the slide S², being actuated by a lever s². In either case the function attained is essentially the same in that the variant slide V, may be advanced or retracted upon and between its supporting ways a', a', on the framework A.

The under side of the variant slide V, is formed with a longitudinal recess v', into which protrudes the upper extremity of an otherwise loose travelling fulcrum stud F, the lower extremity of which is supported in a longitudinal groove l, formed for the purpose in the upper side of the thrust lever L, the fulcrum l', of which journaled in a bracket a², rigidly affixed to the framework

A, of the apparatus, as shown more particularly in Fig. 3, of the drawings, said fulcrum l' , of the thrust lever L , extending through said bearing bracket a^2 , and having rigidly secured to it one arm t , of a toggle T , the other arm t' , to which is pivotally connected the crank arm p , of the power shaft P .

As a consequence the rotation of the power shaft P , will cause its crank arm p , acting through the medium of the toggle joint T , and fulcrum l' , of the thrust lever L , to vibrate the latter back and forth upon its said fulcrum within the limit prescribed by the said crank motion, and hence to shift the position of the travelling fulcrum stud F , within the longitudinal recess v' , in the variant slide V , and as related to the latter, and in accordance with its position upon 20 and between the ways a', a' . Thus in Figs. 1 and 2, the variant slide V , being positioned at the inner extremity of the adjusting screw S , the fulcrum stud F , will be reciprocated from one end of the recess v' , to the other, 25 full stroke, by the rotation of the power shaft P , whereas when the variant slide V , is adjusted to a medial position, as illustrated in Fig. 7, the travel of the fulcrum stud F , will obviously be restricted accordingly.

30 The function of the travelling fulcrum stud F , is to effect and control the movement of the twin rack frame R , by means of which motion is transmitted to the work shaft W , through the medium of the rocker pinions q, q , and mitre gearing actuated thereby as hereinafter set forth, and this is accomplished by reason of the engagement of said travelling fulcrum stud F , with the sides of a slot r , formed for the purpose in the spine or cross bar r' , of said rack frame R , the latter being slidably mounted upon and between longitudinal guide rails a^3, a^3 , on the inner side walls of the framework A , and being formed with the parallel rack arms r^x, r^x , the teeth of which mesh with those of the aforesaid rocker pinions q, q . Each pinion q, q is rigidly secured to the outer end of its rock shaft q' , each rock shaft q' , being mounted on its standard bearing a^4 , 40 rigidly attached to the base plate a^5 , of the frame A , as shown more particularly in Fig. 4, of the drawings. On the inner extremity of each of these said rock shafts q' , is loosely mounted a mitre drive-gear q^2 , each meshing 45 with pinion-mitre gears w, w' , which are loosely mounted on the work shaft W . In other words these mitre drive-gears q^2 , and pinion mitre gears w, w' , are free on their respective shafts (q', W) except when held 50 to rotate therewith by copulative means. To this end each of the mitre drive gears q^2 , is formed with or has rigidly attached to it a ratchet wheel q^3 , with which engages a pawl q^4 , on an arm q^5 , rigidly attached to its rock shaft q' , so that each pawl q^4 , functions to

actuate its drive mitre gear q^2 , intermittently as its rock shaft q' , is actuated intermittently by reason of the engagement of its pinion q , with one of the rack arms r^x , during the reciprocation of the rack frame R ; 70 whereas in the case of the pinion mitre gears w, w' , they are coupled alternately to the work shaft W , by means of a clutch slide w^2 , mounted thereon, and controlled by a shift rod w^3 , said clutch slide w^2 , being formed with coupling tongues w^x , adapted to engage recesses formed for the purpose in the hubs of the pinion-mitre gears w, w' , as will be understood by reference more particularly to Figs. 1, 4, 6 and 7, of the 80 drawings. Hence by the shifting of the clutch slide w^2 , by means of the rod w^3 , one or the other of the pinion mitre gears w , may be coupled to the work shaft W , according to requirements. 85

For instance by shifting the clutch slide w^2 , upon the work shaft W , from engagement with one pinion mitre gear w, w' , to the other the reversal of motion of the work shaft may be effected, since said pinion mitre gears w, w' , are rotated in opposite directions by the mitre drive gears q^2 , as will be obvious by reference more particularly to Fig. 4, of the drawings, it being understood that said mitre drive gears q^2 , as actuated by their respective ratchet wheels q^3 , and pawls q^4 , are rotated in opposite directions as related to each other and to the pinion mitre gears w, w' . To this end the ratchet wheels q^3 , and their pawls q^4 , and ratchet arms q^5 , on their respective rocker shafts q' , are relatively reversed in operative position, so that the reciprocation of the rack frame R , acting on both pinions q , simultaneously will move the rock shafts q' , in opposite directions, so that one pawl will ride idly over its ratchet wheel while the other pawl is in engagement with its ratchet, and vice versa, thereby causing the mitre drive gears q^2 , to alternate in imparting power to the pinion mitre gear which is keyed to the work shaft W . That is to say the mitre drive gears q^2 , ride idly on the rock shafts q' , except when positively driven by their respective ratchets and pawls, so that they alternate in imparting motion to the work shaft W , during the reciprocation of the rack frame R , the racks r^x , of which rock the pinions q , and shafts q' , in opposite directions, as aforesaid. 100 105 110 115 120

By my construction and arrangement of parts change and regulation of speed and power transmission may be effected gradually, as indicated by the line o -max in the diagram Fig. 11, as compared with the other diagram Fig. 10, which represents the old method of intermittent step adjustment. Furthermore, my mechanism operates uniformly and smoothly, and the shifting of gears under the old method of variant speed 125 130 135

is eliminated, hence an applied load may be transmitted gradually without abrupt jerks or intermissions.

It is obvious that in lieu of the crank p , motion may be transmitted from the power shaft P , to the toggle joint T , by an eccentric or equivalent mechanical expedient with like results.

What I claim as my invention and desire 10 to secure by Letters Patent, is:—

Variable speed control mechanism of the character designated, comprising a grooved variant slide, means for adjusting the position of said variant slide, a grooved thrust 15 lever, a travelling fulcrum stud extending into the grooves in said variant slide and

said thrust lever, a rack frame slotted to straddle said travelling fulcrum stud and formed with parallel rack arms, rock shafts having rigidly attached rocker pinions engaging said parallel rack arms, mitre drive gears loosely mounted on said rock shafts, ratchet and pawl means for coupling said mitre drive gears to said rock shafts, a work shaft and mitre pinion gears loosely mounted thereon, clutch means for coupling said mitre pinion gears alternately to said work shaft, a power shaft and means for transmitting motion therefrom to the fulcrum of the said thrust lever, substantially in the 30 manner and for the purpose set forth.

JOSEPH VIGLIANO.
